UNITED STATES PATENT OFFICE.

JAMES A. BISHOP, OF CHICAGO, ILLINOIS.

CONDENSER.

1,395,898.

Specification of Letters Patent.

Patented Nov. 1, 1921.

Application filed May 26, 1919. Serial No. 299,826.

To all whom it may concern:

Be it known that I, JAMES A. BISHOP, a citizen of the United States, residing at Chicago, county of Cook, and State of Illinois, have invented certain new and useful 5 Improvements in Condensers, of which the following is a specification.

The present invention has to do with improvements in condensers such as are used 10 for bringing down or precipitating certain constituents from vapors and gases in which they are carried, as, for example, for the precipitation of constituents from retort shale-oil vapors, gases and other distillates. 15 While the construction herein disclosed is very well adapted for cooling the gases from retort shale ovens, it is not in any wise limited to this particular use, and I do not limit myself to such use except as I may do so 20 in the claims.

The construction herein disclosed is especially adapted for use in localities where cooling water is scarce as, for example, in the arid and semi-arid regions of the western 25 portion of the United States.

One of the objects of the invention is so 30 to construct the condenser or cooler that a maximum portion of heat may be abstracted from the gases by the use of a minimum 35 amount of cooling water. In this connection one object is to so arrange the parts that the temperature may be reduced to the lowest possible point so as to insure a substantially complete condensation and precipitation of the hot vapors.

Another object of the invention is to render 40 the operation of the condenser as nearly automatic as possible so as to insure its proper functioning at all times with a minimum amount of necessary attention and labor.

Other objects and uses of the invention 45 will appear from a detailed description of the same, which consists in the features of construction and combinations of parts hereinafter described and claimed.

Referring to the drawings:

Figure 1 shows a longitudinal section 50 through a condenser construction embodying the features of the present invention. In this figure I have also shown diagrammatically suitable connections from the condenser to an exhaust fan and to a scrubber;

Fig. 2 shows a longitudinal horizontal

section taken on the line 2—2 of Fig. 1, looking in the direction of the arrows;

Fig. 3 shows a vertical cross section taken on the line 3—3 of Fig. 1, looking in the direction of the arrows;

Fig. 4 shows in detail one of the baffles 60 in the condenser pipes; and,

Fig. 5 shows a fragmentary vertical section on the line 5—5 of Fig. 4, looking in the direction of the arrows.

The condenser comprises a series of vertical tubes or pipes 5 in conjunction with upper headers 6, 7, 8, and 9 and lower headers 10, 11 and 12. The number of the vertical pipes or tubes and the number of the upper and lower headers may be increased or reduced largely at the will of the designer, but for purposes of illustration I have shown four upper headers and three lower headers. The fresh gases or vapor enter the upper header 6 through a connection 13, pass down through the corresponding pipes 5 to the lower header 10, pass upwardly through the corresponding pipes to the upper header 7; downwardly through the corresponding pipes to the lower header 11; upwardly through the corresponding pipes to the upper header 8; downwardly through the corresponding pipes to the lower header 12; and upwardly through the corresponding pipes to the upper header 9, whence any remaining gases or vapors are delivered through the connection 14. The fan or blower 15 provides a suction on the connection 14 whereby said gases or vapors are delivered to the scrubber 16, or any other suitable mechanism.

It will be observed that in the illustrations there are four pipes downwardly from the header 6 to the header 10; four pipes upwardly from the header 10 to the header 7; three pipes downwardly from the header 7 to the header 11; three pipes upwardly from the header 11 to the header 8; three pipes downwardly from the header 8 to the header 12; and two pipes upwardly from the header 12 to the header 9. By this arrangement the cross sectional area through the pipes decreases as the vapors approach the point of discharge, this being in harmony with the fact that the volume of the vapors also decreases as certain of their constituents are condensed.

Reference to Figs. 2 and 3 in particular

will reveal the fact that the headers are generally of rectangular cross section while the tubes are generally circular. Any suitable cross sectional form might be substituted, but that illustrated is of advantage in some cases. It will also be observed that the tubes are located in staggered relationship and provide a space 17 between them through which cooling air may be circulated. It will also be observed from examination of Fig. 2 that by reason of the staggered relationship of the tubes, the air is caused to travel in a more or less tortuous path as shown by the arrow 18 in Fig. 2. This tends to throw the air back and forth against the side walls 19 and 20.

The cooling air enters at the end 21 and is discharged from the end 22 in any suitable manner. Such discharge may be effected, for example, by a stack or chimney 23 to which the discharge end 22 is connected by a flue 24, the hot products of combustion from the distilling ovens or other heating structure being introduced into the stack through a pipe 25. The hot gases so introduced into the stack will create a draft therein which will tend to draw the cooling air through the condenser.

As the cooling air is drawn through the condenser it becomes warm as the point of discharge is approached, so that its effect is to increase the draft up the chimney and laterally through the condenser, thereby increasing the air cooling capacity and evaporation. In order to further improve the cooling effect, I have provided means for keeping the side walls 19 and 20 always in more or less moist condition, so that the air thrown against said side walls will evaporate moisture from them and be correspondingly cooled. It is well understood that the evaporation of a relatively small amount of moisture into a body of air results in a very large cooling effect on account of the latent heat of evaporation of the water. By this process every degree of heat carried by the shale vapors contributes to the cooling of these vapors.

As a simple means for maintaining the side walls always moist and for improving the evaporation of moisture through them, the following constructions are illustrated:

The said evaporation walls 19 and 20, to which the air is exposed, are preferably laid in more or less loose and disconnected fashion. The outer casing of the structure should, in such cases, be formed by walls 26 and 27 laid up in tight relationship. In the upper portion of the structure is located a series of spray nozzles or the like 28 facing alternately in opposite directions and receiving water from a pipe 29. Water is delivered to said pipes 29 by a riser 30 to which it is admitted through a valve 31 regulated by a float 32. The lower headers 10, 11, and

12, as well as the lower portions of the walls 19 and 20 are set into a pan or trough 33 which catches any surplus water running down over the inside walls so that the level of the water in said trough rises until the float 32 is raised to thereby close the valve 31. In this manner the delivery of cooling water is automatically regulated in the operation of the condenser.

Two or more vent pipes 34 and 35 should be run lengthwise through the trough so as to carry the cooling air through it to the stack 23, thus cooling the water in the trough. This water may be further cooled by the liberation of compressed ammonia, gas, or other form of gas, sprayed into the pipes 34 and 35 to convert the said trough and water into an ice machine. If desired, also, a vent space 36 may be provided beneath the trough and leading into the stack, so that the entire outer surface of the trough will be cooled more or less by the air flowing through.

The condensate collecting in the lower headers 10, 11 and 12 should be removed therefrom by the pipes 37, 38 and 39 illustrated in Fig. 1, or in any other suitable manner, in order to relieve the condenser of the heat which they carry and to fractionate the products of condensation. A roof 40 is set over the entire length of the structure so as to insure a proper travel of the cooling air through it.

Reference to Fig. 4 will reveal a baffle 41 having a notch 42 in its side portion. These baffles are set into the vertical pipes or tubes 5 with their notches facing alternately in opposite directions, so that the gases flowing through the tubes are compelled to baffle back and forth and from side to side. This action will very greatly improve the cooling effect of the tubes by bringing the gases into intimate contact with the interior of the tubes.

It will be observed that as air is drawn through the condenser, its temperature rises owing to the abstraction of heat from the tubes 5 and their contents, but as its temperature rises, it is capable of abstracting more and more water from the side walls by evaporation. Consequently its cooling capacity increases correspondingly, so that the amount of cooling effect ultimately secured is very much larger than would otherwise be secured.

While I have herein shown and described only a single embodiment of the features of my invention, still I do not limit myself to said embodiment except as I may do so in the claims.

I claim:

1. A condenser of the class described comprising in combination a series of upper headers in horizontal alinement with each other, a series of lower headers located in

- horizontal alinement with each other and beneath the upper headers, the end portions of the lower headers lying beneath the end portions of the upper headers and breaking 5 joints therewith, vertical tubes extending between the upper and lower headers to provide a path of travel for distillate vapors alternately down and up through the successive pipes and the headers, an elongated 10 chamber wherein said headers and pipes are located, the side walls of said chamber comprising bricks, a pan wherein the lower portions of said walls and the lower headers are located, spray nozzles for directing water 15 against the upper portions of the walls, a water header therefor, a valve for controlling the delivery of water to said header, a float for said valve in said pan, and suitable connections for delivering air into one end 20 of said chamber and for delivering air from the other end thereof, substantially as described.
2. A condenser of the class described comprising in combination a series of vertical 25 tubes, upper and lower headers joining together said tubes in groups, a chamber wherein said header and tubes are located, said chamber having brick evaporation walls, a pan wherein the lower portions of 30 said evaporation walls and the lower headers are located, spray nozzles for directing water against the upper portions of said walls, a water header for said nozzles, a valve controlling the delivery of water to 35 said header, a float for said valve in said pan, and suitable connections at the end portions of said chambers for permitting the entry of fresh air and the withdrawal of 40 warm air therefrom, substantially as described.
3. A condenser of the class described comprising in combination an elongated chamber having its evaporation walls formed of brick, means for directing sprays of water 45 against the upper portions of said evaporation walls, a pan for collecting water from the lower edges of the walls, a valve for controlling the delivery of water to the spray nozzles, a float for said valve in said pan, 50 vertically extending vapor tubes in said chamber located in staggered relationship with respect to the travel of air through the chamber past the tubes, and suitable connections for delivering vapors into one end of each pipe and for withdrawing liquids 55 and condensates from the other end thereof, substantially as described.
4. A condenser of the class described comprising in combination a series of vertical vapor tubes located in staggered relationship 60 with respect to the travel of air horizontally between them, brick walls adjacent to said pipes and against which air traveling between the pipes is deflected, spray nozzles for spraying water upon the upper portions 65 of said walls, and means for regulating the delivery of water to said nozzles according to requirements, substantially as described.
5. A condenser of the class described comprising in combination a series of vertical 70 vapor tubes located in staggered relationship with respect to the travel of air between them horizontally, brick walls adjacent to said pipes and against which said air is deflected in its travel, and means for spraying 75 water onto the upper portions of said walls, substantially as described.
6. A condenser of the class described comprising in combination a series of vertical vapor tubes, connections for delivering gas 80 into one end of said tubes and for withdrawing gas from the other end of said tubes, a pan wherein the lower portions of said tubes are immersed, means for delivering water into said pan, and suitable refriger- 85 ator ducts within said pan for refrigeration by ammonia or the like, substantially as described.
7. A condenser of the class described comprising in combination a series of vertical 90 vapor tubes, a series of connections for delivering distillate gas into and removing said gas from said tubes, and a series of baffles within each tube located at various positions of elevation, each baffle lying across 95 the tube and having a notch in one of its side portions for the passage of gas, and the baffles being positioned within their respective tubes with their notches facing alternately in different directions, substantially 100 as described.

JAMES A. BISHOP.
